DESIGN FOR A SIGN.

SPECIFICATION forming part of Design No. 20,839, dated June 16, 1891.

Application filed November 29, 1890. Serial No. 373,072. Term of patent 7 years.

To all whom it may concern:

Be it known that I, ZERO MARX, a citizen of the United States, residing at Chicago, in the county of Cook and State of Illinois, have 5 invented and produced a new and original Design for an Advertising-Sign, of which the following is a specification, reference being had to the accompanying drawing, forming a part thereof and illustrating my design in 10 elevation.

The leading features of my design consist in an advertising-sign having upon its face a representation of a horizontally-disposed barrel, presenting one end to view and sur- 15 mounted by a beer glass or mug resting in upright position upon the barrel, with an arabesque pattern of fanciful configuration disposed upon each side thereof and in the back- ground.

A is the representation of a head portion of 20 a barrel, illustrating it in perspective by a view taken from a point slightly above and more or less centrally in front of the said head portion. The beer glass or mug B stands centrally upon the upper side of the 25 barrel near the head and is of an attractive pattern of the character substantially as shown.

What I claim is—

The design for an advertising-sign, as 30 herein shown and described.

ZERO MARX.
